DESIGN FOR WALL PAPER OR THE LIKE

Frank E. Leitch, Stamford, Conn., assignor to Stamford Wall Paper Company, Incorporated,
Stamford, Conn., a corporation of Delaware

Application January 4, 1940, Serial No. 89,290

Term of patent 3½ years

To all whom it may concern:

Be it known that I, Frank E. Leitch, a citizen of the United States, residing at Stamford, in the county of Fairfield and State of Connecticut, have invented a new, original, and ornamental Design for Wall Paper or the Like, of which the following is a specification, reference being had to the accompanying drawing, forming part thereof.

The drawing is a plan view of wall paper showing my new design, the figure of the drawing shows a complete unit of my design, said unit being repeated in regular succession the entire length of the paper as indicated by the dotted lines.

I claim:

The ornamental design for wall paper or the like, as shown and described.

FRANK E. LEITCH.
